[57] CLAIM

The ornamental design for a reel seat for fishing rod, as shown and described.

DESCRIPTION

FIG. 1 is a top, front and one side perspective view of a reel seat for fishing rod showing my new design; FIG. 2 is a bottom, front and one side perspective view thereof;

FIG. 3 is a rear and one side perspective view thereof; FIG. 4 is a front elevational view thereof;

FIG. 5 is a rear elevational view thereof; FIG. 6 is a side elevational view, the opposite side being a mirror image thereof;

FIG. 7 is a top plan view thereof; and

FIG. 8 is a bottom plan view thereof.
